UNITED STATES PATENT OFFICE

JACQUES G. COLEMAN, OF WOODMERE, NEW YORK, ASSIGNOR, BY MESNE ASSIGNMENTS, TO GILLETTE SAFETY RAZOR COMPANY, OF BOSTON, MASSACHUSETTS, A CORPORATION OF DELAWARE

SAFETY RAZOR

Application filed May 26, 1930. Serial No. 455,632.

The present invention relates to that class of safety razors in which a flexible blade is clamped between a guard member and a blade backing member, positioning studs being provided to retain the blade and backing member in operative relation to the guard. The invention pertains more particularly to that type of the above-mentioned class of safety razors wherein, instead of the usual cylindrical positioning studs, non-cylindrical studs are provided on the blade holder, said last-mentioned studs being adapted to be seated in a longitudinal slot in the blade, the purpose of this arrangement being mainly to lend increased flexibility to the blade for clamping in the blade holder, so as to overcome the danger of the blade cracking or breaking in a lengthwise direction while being bent or under tension.

One of the objects of the invention is to provide a safety razor of the type mentioned in which the cutting edges of the blade may be conveniently adjusted in relation to the longitudinal edges of the guard member, so as to vary, at will, the bite of the blade or to compensate for the loss in width by repeated re-sharpening of the blade.

Another object of the invention is to produce a safety razor of the character referred to, wherein the cutting edges of the blade may be readily set at acute angles to the longitudinal edges of the guard member, so that, in drawing the blade over the face in the ordinary manner, the cutting edge attacks the hair "diagonally" or gradually along a given line, thereby easing the action of the razor and practically eliminating the "pull" of the implement.

A further object of the invention is to so construct the improved blade that it may be used in connection with blade holders including non-cylindrical studs and also with blade holders having cylindrical studs, such as those of the ordinary Gillette type razor.

Still a further object of the invention is to provide a simple and efficient blade holder and blade construction which is capable of manufacture on a commercial scale, or in other words one which is not so difficult to

make as to be beyond the reasonable cost of such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

Two of the many possible embodiments of the invention are illustrated in the accompanying drawings, in which:

Figure 1 is an end view of a razor constructed in accordance with the present invention; Fig. 2 is a section taken on line 2-2 of Fig. 1; Fig. 3 is a section taken on line 3-3 of Fig. 2, part of the backing member being shown in plan view; Fig. 4 is a top plan view of the guard member of the improved razor; Fig. 5 is a bottom plan view of the blade backing member of the construction; Fig. 6 is a plan view of the improved blade; Fig. 7 is a section similar to the one shown in Fig. 3 with the blade in adjusted position; Fig. 8 is a section taken on line 8-8 of Fig. 7; Fig. 9 is a section similar to the one shown in Fig. 8, the elements of the razor being in the positions which they occupy before the blade is being flexed; Fig. 10 is a section similar to the one shown in Fig. 3 of a modification of the invention; Fig. 11 is a bottom plan view of the backing member of the construction illustrated in Fig. 10; Fig. 12 is a section similar to the one shown in Fig. 10 with the blade in adjusted position; and Fig. 13 is a plan view of the blade associated with the structures illustrated in Figs. 10 to 12, inclusive.

Referring now first to Figs. 1 to 9, inclusive, of the drawings the numeral 13 indicates a guard member, provided with suitable guard teeth 14 in its opposite longitudinal edges and having a central hole 15. In its longitudinal axis, the said guard member is

provided on either side of the central hole 15 with two non-circular openings 16 and 17, which are, in the case illustrated, each of oblong configuration. The openings of each set 5 are spaced and the corresponding elements of the two sets are equidistantly located from the transverse center line of the guard member, said line passing through the center of the hole 15. The minor axes of the said openings 10 are disposed in the longitudinal center line of the guard member and their major axes extend transversely of the guard member in parallel relation to one another and, preferably, at right angles to the longitudinal 15 axis of said guard member.

The guard openings 16 are adapted to receive positioning studs 18 which extend from the backing member 19. The transverse cross-section of each positioning stud corresponds to the configuration of the openings 16 to insure proper alignment of the backing member with the guard member. Between the studs 18 is disposed on the backing member a screw-threaded pin 20, adapted to pass 20 through the hole 15 in the guard member and to engage with a threaded socket 21 in a handle 22, for the well-known purpose. The positioning studs 18 are adapted to pass also through a central longitudinal slot 23 in the 25 blade 24, which is of the thin flexible type having two cutting edges 25. The blade slot 23 is provided with a central transverse enlargement 26 and with a transverse enlargement 27 adjacent each of its ends. The central transverse enlargement 26 is adapted to 30 register with the center hole 15 in the guard member of the razor and is adapted to receive the pin 20. Transversely of the blade the length of the slot enlargement 26 exceeds considerably the diameter of the pin 20, to permit shifting of the blade on the guard member toward either of the longitudinal edges thereof.

The blade slot 23 is provided in its longitudinal edges on either side of each enlargement 27 with a notch, those nearer the central enlargement 26 being designated by the numeral 28 and those nearer the transverse blade edges being designated by the numeral 29. 45 The notches 28 are in alignment with the guard openings 16 and the notches 29 with the guard openings 17 when the blade is mounted on a razor.

The blade is provided on each transverse 50 edge thereof with a projection 30, extending beyond the transverse edges of the guard member (Fig. 3) when the blade is positioned thereon, the said projections constituting means by which the blade may be conveniently handled without danger of injuring the hands of the user.

The enlargements 27 of the blade slot are provided for the reason that, although the blade described is particularly adapted to co- 55 operate with the blade holder illustrated in

the drawings, the spacing between the said enlargements is such as to receive cylindrical positioning studs of the backing members of the type of the ordinary Gillette razors on the market.

In assembling the elements of the razor, the blade is placed upon the clamping member, the positioning studs 18 and pin 20 of the latter being extended through the blade slot 23. The guard member is then placed 70 upon the blade, the positioning studs 18 being extended through the openings 16 in the guard member and the pin 20 passed through the guard hole 15. Thereafter the handle 22 is engaged with the pin 20 and partly 75 screwed home. The blade is then centered in the blade holder and the handle screwed home, whereby the elements are clamped together in the manner shown in Figs. 1 to 3, inclusive, of the drawings. If it is intended to shift the blade toward either longitudinal edge of the guard member, the said blade is 80 grasped by its projections 30 and moved to the desired position shown for instance in Figs. 7 to 9, inclusive, of the drawings, before the handle is fully screwed home (Fig. 9).

The modification illustrated in Figs. 10 to 13, inclusive, differs from the one above described in that the positioning studs 18' on the blade backing member 19' thereof cooperate with the blade notches 29 and the openings 17 in the guard member. Furthermore, the slot 23 in the blade 24' is provided in each of its longitudinal edges with only two notches 28 and 29, two notches 28 and 29 being disposed adjacent one slot enlargement 27, and two notches adjacent the other slot enlargement 27. By reason of this arrangement the blade is centered automatically upon the backing member 19' when placed thereon (Fig. 10). From an inspection of Fig. 12 it will be noted that the cutting edges of the blade may be extended at an acute angle to the longitudinal edges of the guard member, one of the positioning studs 18' being engaged with a blade notch 29 in one longitudinal edge of the slot 23 and the other positioning stud with a blade notch 29 in the opposite longitudinal edge of said slot. Of course, the construction illustrated in Figs. 1 to 9, inclusive, permits of such arrangement also. However, the angle of inclination in such case is larger because the positioning studs 18 are disposed nearer to one another than the studs 18'. In Fig. 12 of the drawings the blade is shown in its outermost position. The angle of inclination may be varied from the largest angle shown in Fig. 12 to parallel relation of the blade cutting edges to the longitudinal edges of the guard. 110

From the foregoing it will be noted that the guard member is the same in both constructions illustrated in the drawings, and is thus adapted to co-operate with either one 115

of the blade backing members illustrated in Figs. 5 and 11. It will also be noted that the blades shown in Figs. 6 and 13 of the drawings can be used in connection with 5 either one of said backing members.

What I claim is:—

1. A safety razor comprising blade clamp-
ing members, a blade adapted to fit between
said members, means to clamp said members
10 on said blade including a screw-threaded
spindle on one of said clamping members,
said blade having a central longitudinal slot
provided with a plurality of transverse en-
largements, and positioning studs on one of
15 said clamping members adapted to enter said
blade slot in alignment with said enlarge-
ments, said spindle passing through said
blade slot and said transverse enlargements
being of such contour that the blade may be
20 displaced angularly around said spindle, as
a fulcrum, with reference to said blade clamp-
ing members. 75
2. In a safety razor according to claim 1,
said blade slot being provided with a central
25 transverse enlargement, said enlargement
having a major axis exceeding that of the
diameter of said spindle, whereby said blade
may be shifted transversely on said clamping
members in relation to the longitudinal edges
30 of the latter to bring either one of its cutting
edges closer to a longitudinal edge of a
clamping member in parallel relation to the
last-named edge. 80
3. A safety razor, comprising blade clamp-
35 ing members, a blade adapted to fit between
said members, means to clamp said members
on said blade including a screw-threaded
spindle on one of said clamping members,
said blade having a central longitudinal slot
40 provided with a plurality of transverse en-
largements, one enlargement being formed
at each end of the slot and forming, in com-
bination with the ends of the blade, an elon-
gated flexing hinge at each of the blade ends,
45 and positioning studs on one of said clamp-
ing members adapted to enter said blade slot
in alignment with some of said enlargements,
said spindle passing through said blade slot
and said transverse enlargements being of
50 such contour that the blade may be both
shifted and displaced angularly around said
spindle, as a fulcrum, with reference to said
blade clamping members. 85
4. In a safety razor according to claim 3,
55 said blade slot being provided with a central
transverse enlargement, said enlargement
having a major axis exceeding that of the
diameter of said spindle, whereby said blade
60 may be shifted transversely on said clamping
members in relation to the longitudinal edges
of the latter to bring either one of its cutting
edges closer to a longitudinal edge of a clamp-
ing member in parallel relation to the last-
65 named edge. 90
